Application June 8, 1937, Serial No. 147,015

3 Claims. (Cl. 2—116)

This invention relates to shirts and has particular reference to shirts of the pullover type.

In application Serial No. 733,953, filed July 6, 1934, there is illustrated and described a shirt of the pullover type, which is characteristic in that no buttons or other fastening means are required, the integral collar being held closed by the necktie. Among the advantages of such a shirt are that it may be rapidly donned and removed, having no buttons to fasten and unfasten, and will not be readily damaged by laundering and use, which renders the shirt particularly useful for sport wear.

In accordance with the present invention, a pullover shirt of the no-button type disclosed in said application is provided, which is so constructed and arranged that the collar is urged toward closed position without the necessity of starch or other stiffening means for holding the collar in closed form, and without requiring the use of a necktie for that purpose, except when the fully closed position of the collar is desired.

The preferred embodiment of the invention comprises a shirt whose body may be constructed in the conventional way except that the slit in the front extends downwardly from the collar to approximately the middle of the chest of the wearer, providing with the neck aperture an opening of sufficient size to accommodate the head of the wearer in donning and removing the shirt. The rear half of the neck band of the attached collar is horizontal and the front half thereof is inclined downwardly from the sides of the neck of the wearer to the front at a relatively sharp angle, and this structure causes the unattached front ends of the collar band to automatically tend to fall toward closed position without fastening means. The two sides of the front slit are preferably, but not necessarily, reinforced slightly in order to aid the self-closing tendency of the collar band and to cause the shirt front to lie flat and smooth.

For a more complete understanding of the invention, reference may be had to the accompanying drawing, in which:

Figure 1 is a front view of a shirt embodying the present invention;

Fig. 2 is a development of the collar thereof illustrating the construction and arrangement of the neck band thereof;

Fig. 3 is a cross-section, as seen along the line 3—3 of Fig. 1, illustrating the construction of the slit front; and

Fig. 4 illustrates the manner in which the collar may be folded back from the throat.

Referring to the drawing, numeral 10 designates the body of the shirt, which is of woven or knitted fabric and may be constructed in the conventional way. The body 10 is provided with sleeves 11, either short, as shown, or longer, but preferably without cuffs or with buttonless cuffs.

The slit 12 in the front or bosom of the shirt body 10 is relatively short, extending down to approximately the middle of the chest of the wearer, although its length is determined principally by a size of opening formed jointly by it and the neck aperture 13, which is only large enough to comfortably accommodate the head of the wearer in donning and removing the shirt. For example, a length of approximately 7½ inches for slit 12 has been found satisfactory.

The side edges 14 and 15 forming the front slit 12 are connected at their upper ends to the respective overlapping tabs 16 and 17 of the collar band 18 and are stitched together at their lower ends 19 with a relatively wide overlap, tending to hold them in overlapped position.

As is illustrated in Fig. 3, the side edges 14 and 15 of the front slit 12 are preferably, but not necessarily, reinforced, so that they are stiffened to a certain extent. This structure causes the side edges 14 and 15 to tend to assume and hold their normal overlapped position and also serves to hold the bosom or front of the shirt smooth and flat.

The neck band 18 is shaped as illustrated in the development of Fig. 2, and includes the aforementioned overlapping tabs 16 and 17, which are well-rounded and merge at their front edges with the corresponding side edges 14 and 15 of the bosom slit 12 and at their upper edges with the inclined edges 20 and 21 of the front half of the collar band 18, the rear half 22 of which, between lines A—A, is relatively straight, as shown. The inclination of 20, 21 from the horizontal should not be materially less than 8—10°. A collar 23 of any desirable shape is stitched to the band as shown.

The lines 20, 21 and 22 need not be straight and their juncture angles on the lines A—A are not sharp, but the front parts of the collar band must be inclined downwardly from the sides of the neck of the wearer to obtain the self-closing tendency of the collar according to the present invention. Thus, the usual curved fold line of collars, provided in order that the overlapped collar and neck band will conform to the curvature of the neck, will not suffice; the front half of the collar must be curved or otherwise inclined more sharply downward.

- In use the special shape of the neck band 18 tends to hold the collar 23 in closed position about the neck of the wearer, the downward pitch of the front 20, 21 thereof causing it to hug the neck. This tendency is aided to a certain extent by the 5 overlap and stiffness of the front side edges 14 and 15 of the bosom slit 12. Obviously, the collar is not urged to and held in completely closed position without aid, and a necktie is used for that purpose.
- 10 This self-closing tendency of the collar enables the shirt to be worn with comfort in unfastened condition, i. e., without buttons, necktie, or other fastening means, even during violent exercise, without the creeping down the back of the 15 wearer, the characteristic tendency of open neck shirts under such circumstances. If it is desired to wear the shirt wide open at the neck the collar and front may be folded back as shown in Fig. 4, the collar breaking at the lines A—A because of the shape of the neck band. Thus when once folded back as shown, the collar will remain in that position. Other advantages accruing to a shirt of the present construction are apparent.
- 20 While a preferred embodiment of the invention has been illustrated and described herein, it is to be understood that the invention is not limited thereby, but is susceptible of changes in form and detail within the scope of the appended 25 claims.
- 25 I claim:
1. In a shirt having a front opening, the combination of an attached neck-band therefor having upper and lower edges, each edge having a relatively horizontal center portion and end portions inclined downwardly at an angle to said 30

center portion, from the sides of the neck of the wearer to the front opening, whereby the neck-band tends to embrace the neck of the wearer to urge the front opening toward closed position without requiring fastening means for that purpose. 5

2. In a shirt having a front opening, the combination of reinforcing means on the opposite edges of the front opening, said edges being normally overlapped and free of fastening means, a 10 neck-band for the shirt having its center portion relatively straight along the upper and lower edge and the upper edges of its end portions inclined downwardly at an angle to said straight center portion edge from approximately the sides of the 15 neck of the wearer, and a collar or the neck band, the said downward inclination of said neck band ends tending to urge the collar toward closed position.

3. In a shirt providing a front opening, the 20 combination of a neck-band therefor having a relatively horizontal center portion of a length to extend substantially around the back to the sides of the neck of the wearer, end portions on said neck-band having upper and lower edges extending downwardly at an angle to said center portion from substantially the sides of the neck of the wearer to the front opening of the shirt, and overlapping tabs on the extremities of said neck-band end portions merging with the corresponding 25 sides of said front opening, the said downward inclination of said neck-band ends tending to urge and hold said tabs in said overlapped condition. 30

JOHN DAVID. 35
